UNITED STATES PATENT OFFICE.

RAYMOND E. CRANE, OF CHICAGO, ILLINOIS.

DESIGN FOR A URINAL.

49,012.

Specification for Design.

Patented May 9, 1916.

Application filed February 19, 1916. Serial No. 79,467. Term of patent 14 years.

To all whom it may concern:

Be it known that I, RAYMOND E. CRANE, a citizen of the United States, residing at Chicago, in the county of Cook and State of Illinois, have invented a new, original, and ornamental Design for Urinals, of which the following is a specification, reference being had to the accompanying drawing, forming part thereof.

The figure is a front view in perspective of a stall urinal showing my new design.

I claim:

The design for a urinal as shown.

R. E. CRANE.
